Inventor
BENEDICT E. WILLETT.

By *Edward Reed*

Attorney

UNITED STATES PATENT OFFICE.

BENEDICT E. WILLETT, OF DAYTON, OHIO.

STEPLADDER.

Application filed January 23, 1922. Serial No. 531,117.

To all whom it may concern:

Be it known that I, BENEDICT E. WILLETT, a citizen of the United States, residing at Dayton, in the county of Montgomery and 5 State of Ohio, have invented certain new and useful Improvements in Stepladders, of which the following is a specification, reference being had therein to the accompanying drawing.

10 This invention relates to step ladders and the like and is in the nature of an improvement upon the structure shown in the application for patent filed by me June 6, 1921, Serial No. 475,299.

15 One object of the invention is to provide a structure of this kind which will be simple in construction, of a light weight, and of a strong rigid character.

20 A further object of the invention is to provide such a structure having a platform of ample proportions, upon which the occupant may stand, and having a guard rail at each side of said platform, said structure being so constructed that it will fold into 25 compact form with the several parts thereof extending approximately parallel one with the other.

25 A further object of the invention is to provide such a structure with a retaining device to secure a pail or the like on a work supporting member.

Other objects of the invention will appear as the structure is described in detail.

In the accompanying drawings Fig. 1 is 35 a side elevation of a step ladder embodying my invention, showing the same in its extended position; Fig. 2 is a similar view showing the ladder in a collapsed position, the pail holding device being omitted; Fig. 40 3 is a front elevation of the ladder in its collapsed position; Fig. 4 is a section view taken on a line just above the platform of Fig. 1; Fig. 5 is a sectional view taken through the platform with the movable portion of the platform in its elevated position; Fig. 6 is a detail view of a portion of the 45 rear frame; Fig. 7 is a detail view of the pail retaining device; and Fig. 8 is a detail view of the yieldable stop on the work 50 support.

In these drawings I have illustrated one embodiment of my invention and have shown the same as comprising a front frame, which, in the present instance, is provided with 55 steps. This front frame is supported in an

upright position by a rear frame of greater height than the front frame and the front frame has its upper end spaced from the rear frame and is connected to the rear frame by a suitable spacing device which will permit the structure to be collapsed, that is, one frame moved toward the other.

As here shown, the front frame consists of two upright members 1 which are preferably of wood, and are connected one to the other by transverse members 2 constituting steps. These steps are preferably rigidly secured at their ends to the respective upright members and in the present construction sections of angle iron 3 are rigidly secured to the respective side members and the steps are supported by securing them to these angle irons. The rear frame consists of two upright members 4 which are of a height considerably greater than the height of the 75 upright members 1 and are connected one to the other by transverse members 5, 6 and 7, the member 7 being in the present instance arranged at the top of the rear frame and constituting a work supporting member, or 80 platform. The lower transverse member 5 is in the nature of a bar of metal rigidly secured at its ends to the respective upright members, which are preferably of wood. This bar, and the adjacent portions of the 85 upright members are braced one against the other by brace bars 8 having their intermediate portions bent inwardly and secured to the bar 5 at points spaced from the respective side members. The upper and lower 90 ends of the brace bars 8 are rigidly secured to the respective side members above and below the bar 5. The transverse member 6 is also in the form of a bar of metal which is braced against the side members by means 95 of inclined brace bars 9 secured at their upper ends to the respective side members and at their lower ends to the transverse bar 6 at points spaced from the ends thereof. In this manner, not only are the bar 6 and the 100 adjacent portions of the side members 4 braced one against the other, but the bar is reinforced and strengthened so that it will form a firm support for the supplemental step or platform, as will be herein- 105 after described.

The front frame has its upper end spaced from the rear frame and is connected to the rear frame by suitable spacing devices which 110 preferably extend between the upper end of

the front frame and an intermediate portion of the rear frame. As here shown, the spacing members are in the form of toggles, each of which consists of a bar 10 pivotally connected at its rear end with the rear frame and having its front end supported by the front frame, the bar extending across the full space between the two frames. As here shown, the forward end of each bar 10 rests upon the upper end of the adjacent side member 1 of the front frame and is held against lateral movement relatively thereto by a metal plate 11 which is rigidly secured to the upper end of each frame member and projects slightly above the same. The forward end of the bar is not connected with the front frame but is movable toward and from the same. The bars 10 are connected with the front frame members by links, or bars, 12, pivotally connected at their rear ends with the respective bars 10 between the ends thereof and pivotally connected with the front frame, preferably by riveting, or otherwise securing, the bars 12 to the metal plates 11. This construction constitutes each spacing member a toggle, one member of which extends past its point of pivotal connection with the other member and is supported by one of the frame members. When the structure is in its extended position the several centers of each toggle will lie in the same plane and one member of the toggle being supported at each end by the respective frame members it will be apparent that the toggle is very rigidly braced against downward movement and not only constitutes a rigid connection between the two frame members but is also of sufficient strength to constitute a support for a platform on which the occupant may stand. The spacing device is further reinforced by brace bars 13 arranged at the opposite sides of the structure and pivotally connected at their upper ends with the respective bars 10 and pivotally connected at their lower ends with the respective side members 1 of the front frame at points some distance below the top thereof.

The spacing devices also constitute a support for a platform and to this end I prefer that the bars 10 should be in the form of angle iron bars having one flange extending inwardly from the lower edge thereof and forming a support for the platform 14. This platform may be secured to the bars 10 in any suitable manner, but in the present instance I have shown the same as comprising two parts, the forward portion of which is rigidly and permanently secured to the bars 10 and the rearward portion of which is adapted to be supported in an elevated position to constitute a supplemental step to the ladder. To this end the rear portion of the platform, which is shown at 15, rests loosely upon the flanges of the bars 10 and is con-

nected therewith by means of links 16 which are pivotally connected at their forward ends to the bars 10 near the forward end of the movable section 15 of the platform and are pivotally connected at their rear ends to the edges of the platform section near the rear thereof. The platform section is preferably reinforced by angle irons 17 which afford a firm connection for the ends of the links. When the platform section 15 is in its normal position, in line with the section 14 of the platform, the links will lie between the edges thereof and the vertical flanges of the bars 10. By lifting the rear section, turning the same up-side-down, and moving the links 16 into vertical positions, the platform sections 15 may be connected with the transverse bar 6 of the rear frame by means of the hook shaped ends 18 of the angle bars 17, thus providing a supplemental step for the ladder.

Guard rails 19 are arranged on opposite sides of the platform and extend from the upper end of the rear frame to the upper end of the lower frame. These bars are pivotally connected with the respective frame members and as here shown the upper ends thereof are connected with gusset plates 20 which brace the work supporting member 7 and the lower ends are pivotally connected with portions 21 of the links 12 which extend forwardly beyond the points of connection of said links with the side members 1 of the front frame.

It will be apparent that the structure may be folded by moving the rear frame upwardly and toward the front frame, this being accomplished by elevating the forward edge of the platform, thus breaking the toggles of the spacing device and moving the members one toward the other. This movement of the members causes the bars 10 and the platform carried thereby to assume a position alongside of the rear frame, in which position it is held by the links 12 and the brace bars 13. The lower ends of the guard rails 19 are carried downwardly and rearwardly by the end portions 21 of the links 12, so that these rails also extend lengthwise of the frame members, thus enabling the whole structure to be folded or collapsed into a compact form. When collapsed the weight of the ladder may be supported on the front frame and by placing the upper end of the rear frame against a wall, or other structure, the front frame may be utilized as an ordinary ladder. If desired, the rear frame members 4 which are preferably formed of wood of comparatively small dimensions, may be reinforced by metal strips 22 arranged along the sides thereof and rigidly secured thereto by rivets, or the like.

I have also provided means for retaining a pail or the like upon the work supporting

member 7 and, as here shown, this device comprises a rod 23 slidably mounted in the member 7 and having a hook shaped upper end 24 adapted to engage over the edge of a 5 pail, as shown at 25. That portion of the bar below the member 7 is guided in a vertical bearing 26 secured to one of the upright members 4, and a spring 27 confined between the member 7 and a stop 28 at the lower end 10 of the rod tends to hold the hook shaped end thereof in engagement with the pail and prevent the displacement of the latter. The rod may be held against rotation in any suitable way, as by using a non-circular rod 15 and opening. I also prefer to provide the member 7 with a stud, or projection, 29 extending slightly above the surface thereof to engage within the lower edge of the rim of the pail and prevent the slipping of the 20 pail away from the rod. To permit a flat bottom pail to rest flat upon the supporting member the stud 29 is yieldable, it being preferably supported by a spring 30 mounted in an opening in the member 7.

25 While I have shown and described one embodiment of my invention I wish it to be understood that I do not desire to be limited to the details thereof as various modifications may occur to a person skilled 30 in the art.

Having now fully described my invention what I claim as new and desire to secure by Letters Patent is:

1. In a structure of the character described, a front frame, a rear frame to support said front frame, said front frame being of less height than said rear frame and having its upper end spaced therefrom, and a spacing device so connected with said frames 35 as to permit the rear frame to be moved upwardly and toward the front frame to collapse said structure.

2. In a structure of the character described, a front frame, a rear frame to support said front frame, said front frame being of less height than said rear frame and having its upper end spaced therefrom, a spacing device so connected with said frames as to permit the rear frame to be moved upwardly and toward the front frame to collapse said structure, and a platform pivotally connected with one of said frames to permit it to be moved into a position in 50 which it will extend lengthwise of said frames when said structure is collapsed.

3. In a structure of the character described, a front frame, a rear frame to support said front frame, said front frame being of less height than said rear frame and having its upper end spaced therefrom, a spacing device pivotally connected with said 55 frames to permit the rear frame to be moved upwardly and toward the front frame to collapse said structure, and a platform carried by said spacing device and adapted to be

moved into a position extending lengthwise of said frame members when said structure is collapsed.

4. In a structure of the character described, a front frame, a rear frame to support said front frame, said front frame being of a less height than said rear frame and having its upper end spaced therefrom, and a spacing device comprising toggles, each having one member pivotally connected with said front frame at the upper end thereof and having its other member pivotally connected with said rear frame at a point spaced from the upper end thereof, and a platform carried by said spacing device. 70

5. In a structure of the character described, a front frame, a rear frame to support said front frame, said front frame being of a less height than said rear frame and having its upper end spaced therefrom, a spacing device comprising toggles, each having one member pivotally connected with said front frame and having its other member pivotally connected with said rear frame, one member of each toggle extending beyond its pivotal connection with the other member of that toggle, and being supported by one of said frames and a platform carried by said spacing device. 85

6. In a structure of the character described, a front frame, a rear frame to support said front frame, said front frame being of a less height than said rear frame and having its upper end spaced therefrom, a spacing device comprising toggles each having one member pivotally connected with said front frame and having its other member pivotally connected with said rear frame, and brace bars each pivotally connected at one end with one member of one of said toggles and pivotally connected at its other end with one of said frames at a point below said toggle. 100

7. In a structure of the character described, a front frame, a rear frame to support said front frame, said front frame being of less height than said rear frame and having its upper end spaced therefrom, a platform supporting device extending between the upper end of the front frame and an intermediate portion of the rear frame, and comprising two parts, each of which comprises two members pivotally connected one to the other and having their opposite ends pivotally connected with the respective frames, and means to support the intermediate portions of said parts against downward movement. 110

8. In a structure of the character described, a front frame, a rear frame to support said front frame, said front frame being of less height than said rear frame and having its upper end spaced therefrom, a platform supporting device extending be- 125

tween the upper end of the front frame and an intermediate portion of the rear frame, and comprising two parts each of which comprises two members pivotally connected 5 one to the other and having their opposite ends pivotally connected with the respective frames, one member of each part of said platform supporting device having a portion to engage one of said frame members to limit the downward movement of 10 the intermediate portions of said parts.

9. In a structure of the character described, a front frame, a rear frame to support said front frame, said front frame 15 being of less height than said rear frame and having its upper end spaced therefrom, a platform supporting device extending between the upper end of the front frame and an intermediate portion of the rear frame, 20 and comprising two parts each of which comprises two members pivotally connected one to the other and having their opposite ends pivotally connected with the respective frames, brace bars each pivotally connected 25 with one member of one part of said supporting device and pivotally connected at its other end with one of said frame members at a point below said supporting device.

30 10. In a structure of the character described, a front frame, a rear frame to support said front frame, said front frame having its upper end spaced from said rear frame, bars pivotally connected at their rear ends to the respective sides of said rear frame and having their forward ends supported by said front frame, other bars pivotally connected with the respective first mentioned bars at points between said 40 frames and pivotally connected with said front frame, said bars constituting the sole means for controlling the relative positions of said frames.

11. In a structure of the character described, a front frame, a rear frame to support said front frame, said front frame having its upper end spaced from said rear frame, bars pivotally connected at their rear ends to the respective sides of said rear 50 frame and having their forward ends supported by said front frame, other bars pivotally connected with the respective first mentioned bars at points between said frames, and pivotally connected with said 55 front frame, and a platform carried by said first mentioned bars and arranged between said frames.

60 12. In a structure of the character described, a front frame, a rear frame to support said front frame, said front frame being of less height than said rear frame and having its upper end spaced therefrom, a spacing device so connected with said frames as to permit the rear frame to be moved up- 65 wardly and toward the front frame to col-

lapse said structure, and guard rails arranged at the respective sides of said structure and pivotally connected with the upper portions of said front and rear frames.

13. In a structure of the character described, a front frame, a rear frame to support said front frame, said front frame being of a less height than said rear frame and having its upper end spaced therefrom, a spacing device comprising toggles each having one member pivotally connected with said front frame and having its other member pivotally connected with said rear frame, and brace bars each pivotally connected at one end with one member of one of said toggles and pivotally connected at its other end with one of said frames at a point below said toggle, and guard rails arranged at the respective sides of said structure and pivotally connected with the upper portions of said front and rear frames.

14. In a structure of the character described, a front frame, a rear frame to support said front frame, said front frame being of less height than said rear frame and having its upper end spaced therefrom, a platform supporting device extending between the upper end of the front frame and an intermediate portion of the rear frame, and comprising two parts, each of which 95 comprises two members pivotally connected one to the other and having their opposite ends pivotally connected with the respective frames, and means to support the intermediate portions of said parts against downward movement, and guard rails arranged at the respective sides of said structure and pivotally connected with the upper portions of said front and rear frames.

15. In a structure of the character described, a front frame, a rear frame to support said front frame, said front frame having its upper end spaced from said rear frame, bars pivotally connected at their rear ends to the respective sides of said rear frame and having their forward ends supported by said front frame, other bars pivotally connected with the respective first mentioned bars at points between said frames and pivotally connected with said front frame, and having parts extending forwardly beyond their axes, and guard rails arranged at the respective sides of said structure, pivotally connected at their upper ends to said rear frame and pivotally connected at their lower ends to the forwardly extending parts of the last mentioned bars.

16. In a structure of the character described, a front frame, a rear frame to support said front frame, said front frame being of less height than said rear frame and having its upper end spaced therefrom, bars extending between said front frame and the upper end of said rear frame, having their ends pivotally connected with said rear 120

frame, and having their front ends supported by said front frame, links each pivotally connected at one end to one of said bars between the ends thereof and pivotally connected at its other end with said front frame, a platform supported by said bars, and guard rails arranged on the opposite sides of said platform and each pivotally connected at one end with the upper end of said rear frame and pivotally connected at its lower end with the upper end of said front frame.

17. In a structure of the character described, a front frame, a rear frame to support said front frame, said front frame being of less height than said rear frame and having its upper end spaced therefrom, bars extending between said front frame and the upper end of said rear frame, having their rear ends pivotally connected with said rear frame and having their front ends supported by said front frame, links each pivotally connected at one end to one of said bars between the ends thereof and pivotally connected at its other end with said front frame, each of said links having a part extending forwardly beyond its point of connection with said front frame, a platform carried by said bars, and guard rails pivotally connected at their upper ends with the upper portion of said rear frame and pivotally connected at their lower ends with the forwardly extending portions of the respective links.

18. In a structure of the character described, a front frame, a rear frame to support said front frame, said front frame having its upper end spaced from said rear frame, angle bars extending between said frames and each having a flange extending inwardly from the lower edge thereof, each of said angle bars being pivotally connected at its rear end with the rear frame and being supported at its front end on said front frame, links extending parallel with said angle bars, pivotally connected at their rear ends with the respective bars, and pivotally connected at their forward ends with said front frame, a platform supported by the inwardly extending flanges of said bars, and brace bars pivotally connected with

said angle bars in the rear of their points of connection with said links, and pivotally connected at their lower ends with said front frame.

19. In a structure of the character described, a front frame, a rear frame to support said front frame, said front frame being of less height than said rear frame and having its upper end spaced therefrom, means for spacing said frames one from the other, a work supporting member carried at its extreme upper end by said rear frame, a rod mounted for vertical movement adjacent to said work supporting member and having a hook shaped upper end, and a spring acting on said rod to move the same downwardly.

20. In a step ladder or the like, a work supporting member, a retaining member having a part adapted to engage over the edge of a pail or the like, and a spring tending to move said retaining member toward said work supporting member and a yieldable projection carried by and extending above said work supporting member adjacent to said retaining member.

21. In a step ladder or the like having a work supporting member provided with a flat upper surface, a rod mounted on said ladder below said work supporting member for vertical reciprocating movement relatively to said work supporting member and having a hook shaped upper end extending above said work supporting member to engage a receptacle supported by said work supporting member, and a spring acting on said rod to move the same downwardly.

22. In a step ladder or the like having a work supporting member, a rod mounted for vertical reciprocating movement relatively to said work supporting member and having a hook shaped upper end, a spring acting on said rod to move the same downwardly, and a yieldable stud mounted on said work supporting member adjacent to said rod.

In testimony whereof, I affix my signature hereto.

BENEDICT E. WILLETT.
